LEWIS FERRY MOODY, OF PHILADELPHIA, PENNSYLVANIA

HYDRAULIC PUMP

Original application filed August 21, 1920, Serial No. 405,185, and in Canada April 3, 1923. Divided and this application filed June 15, 1923. Serial No. 645,537.

This invention relates to hydraulic pumps and particularly to those of the double or twin type.

The object of my invention is to provide a pump of this character in which the flow therethrough shall proceed along smooth lines and without losses due to eddies, disturbances or sudden changes in direction of flow. A further object is to provide a pump 10 of this character which is simple in construction and formed of but few parts.

Numerous other objects and advantages will appear from the following description taken in connection with the accompanying 15 drawing which represents in vertical section, partly in elevation, a pump embodying my invention and wherein 10 represents a central volute outlet casing, 11 and 12 similar intake casings which are bolted to the outlet casing 20 at 16, and 13 and 14 represent similar rotary impellers mounted upon a central driving shaft 15. The intake casings 11 and 12 are each formed with an intake passage 17, 18 leading to the helically inclined guide vanes 25 19 and 20. The intake passages may be of the single or double volute form and serve to direct the water from a general radial direction into an axial direction at 23, 23. From these points the passages 17, 18 turn 30 outwardly forming annular vane free chambers 21, 22 which communicate with the impellers 13 and 14. The passages through the impellers continue to curve outwardly without abrupt change in direction and communicate at their discharge ends with passages 26, 27. These passages are formed between the outer wall 30 of the casing 10 and the wall of a central core 28 supported from the wall 30 by helically inclined guide vanes 35 29, 29.

The impellers 13 and 14 are keyed or otherwise secured on the shaft 15 and are held against lateral displacement by means of an 40 enlargement 32 on the shaft 15 and a nut 33 also on the shaft. The nut and enlargement serve to force the impellers against a central 45 spacing sleeve 34. The enlargement 32 and nut 33 have each a tapering outer surface 50 which forms an unbroken continuation of the

inner wall of the passage through the impeller.

Similarly the wall of core 28 forms an outwardly inclined smooth continuation of the inner wall of the passage through each of the 55 impellers.

Shaft 15 is supported by inwardly extending bearings 36, 37 formed in the walls of the intake casings 11, 12. The vanes 19 and 20 connect the bearings at their inner ends 60 with the wall of the intake passage and so assist in supporting the bearings and in forming a rigid construction.

In practice the water entering through the 65 passages 17 and 18 is given the desired degree of whirl by the entrance vanes 19 and 20 and thence passing through the vane free chambers 21 and 22 is delivered to the impellers 13 and 14 in the form of solid whirling streams. Issuing from the impellers the 70 flows pass outwardly through the diagonally inclined outlet passages 26 and 27 between the helically inclined guide vanes 29, 29 into the volute outlet conduit. In proceeding from the impeller the flow is given a gradual 75 deceleration in order that the velocity head may be efficiently converted into pressure head.

The casings 10, 11 and 12 may be readily 80 constructed of castings and the entire pump may be easily assembled as will be seen by an inspection of the drawing. The casings will ordinarily be in two pieces divided on a horizontal plane containing the axis, to facilitate 85 removal of the shaft and impellers.

The pump of this invention is particularly 90 adapted for arrangement in the horizontal shaft position. The outflow will be gradually decelerated along smooth spiral lines and without losses due to eddies and disturbances 95 and sudden changes of direction of the flow. In this invention, the velocity reduction is accomplished by wrapping a single large diffusion passage around the circumference of the discharge space from the impellers. The discharge from the impellers has a whirl 100 around the axis and annular diffusion spaces 26 and 27 are provided in which the water can whirl freely. These chambers diverge from the axis and gradually curve toward but 105

not completely to the radial direction thus causing the flows to enter volute 10, in directions which diagonally cross each other, without flow disturbance or eddy currents being created at the point of mergence. The diagonal feature of the passages is plainly observed from the drawing from which it is to be noted that if the passages or chambers 26, 27 had their center lines extended they would diagonally cross each other. In a more specific aspect of this feature the corresponding sides of the respective passages will also diagonally cross each other, if extended into the volute casing. The avoidance of flow disturbance is because both flows have a whirling action in the same direction so that they merge with each other along tangential lines rather than along straight non-whirling lines which would tend to give a head-on action between the flows with consequent excessive eddying at the junction of mergence. It is by the utilization of the above principle that it is possible to materially reduce the diameter of the volute 10 rather than have a large diameter volute such as is ordinarily used when passages corresponding to 26 and 27 turn completely to a radial direction before discharging into the volute. Thus I am able to build not only a more economical construction but also one that requires less space for a given capacity. As the water recedes from the axis, the whirl is decreased by the principle of the conservation of moment of momentum in accordance with which $r c_v =$ a constant, r being the radius and c_v the velocity of whirl.

To continue the diffusing action, the volute casing 10 provides a long spiral chamber wrapped around the circumference of the discharge passages from the impellers. In these passages, the whirling component of the discharge velocity from the impellers is reduced to a low value along smooth lines efficiently converting the velocity head of whirl into effective pressure head in the discharge. The diffusion action for the flow from each runner is produced first by an enlarging, diverging annular chamber free of vanes, then a continuation of this chamber containing, if necessary for mechanical reasons, stay vanes designed to conform to the flow and to interfere as little as possible with it, and finally a long spiral diffusion space receiving the discharge from the two annular chambers and wound around the circumference of these chambers.

The outflow by these means is continuously and gradually decelerated as to all of its components so that a maximum portion of its velocity head is efficiently converted into effective pressure head in the discharge.

In pumps of the spiral type to which this invention applies the recovery of the energy of the water discharged from the impellers is an extremely important part of the hydraulic

action of the pump, since this energy represents a value in high speed pumps of this type which is large compared to the net head against which the pump is delivering.

This application is a division of my co-pending application Ser. No. 405,185, filed August 21, 1920.

I claim:

1. A rotary hydraulic pump having in combination two oppositely disposed unshrouded impellers of approximately axial flow type and a single volute discharge casing receiving the discharge from both of said impellers, said impellers operating within chambers bounded by surfaces of revolution generated by lines of gradual curvature smoothly merging into the surface of said volute discharge casing, said chambers being so disposed that their center lines diagonally cross each other when extended, the chambers comprising vane-free annular spaces adapted to receive water directly from said impellers while the remainder of each of said chambers have therein a plurality of guide vanes.

2. A rotary hydraulic pump having in combination two opposed impellers of unshrouded high speed type, a converging conduit for each impeller adapted for acceleration of the water on its way to the impeller, a diverging conduit adapted to receive water from each impeller with a high velocity whirl in the same direction as the rotation of the impeller and to decelerate said water on its way from the impeller, said conduits being so disposed relative to each other that the surfaces thereof if extended would diagonally cross each other, and a common volute casing receiving the discharge from both of said diverging conduits.

3. In a rotary hydraulic pump two oppositely disposed unshrouded impellers of the type having a large component of axial flow in combination with a converging inflow conduit for each of said impellers comprising means for imparting whirl about the impeller axis to the water entering the impellers, means forming passages in which said impellers operate, said passages being so disposed relative to each other that their surfaces would diagonally cross each other if extended, and a common volute discharge conduit receiving the flow from both impellers in a diagonal direction.

4. A diffuser for a hydraulic pump comprising a volute passage adapted to decelerate the flow and having a plurality of diagonal annular entrance spaces so disposed relative to each other that if extended their center lines would diagonally cross each other, said spaces having vane-free annular passages and a plurality of helically curved guide vanes.

5. In a double pump the combination with a central volute passage supporting a central

core of a diagonal runner on each side thereof and a plurality of diagonal outlet passages leading from the runners to the volute passage and so disposed that their center lines if extended would diagonally cross each other whereby fluid is discharged into the volute passage in diagonal directions.

5 6. In a double rotary hydraulic pump a pair of unshrouded diagonal outward flow impellers in combination with a volute discharge conduit wrapped in a single turn around said impellers and having annular passages thereto from said impellers, said passages comprising vane free annular spaces 10 adapted to receive water directly from said impellers, the remainder of each of said passages having therein a plurality of helically curved guide vanes.

15 7. In a twin hydraulic pump, a central outlet casing and a pair of inlet casings secured to said outlet casing at opposite sides thereof, said inlet and outlet casings being formed with continuous inlet and outlet passages, a pair of impellers in said passages, a shaft 20 upon which said impellers are mounted, the wall of each of said inlet casings being formed with an inwardly projecting bearing for said shaft and guide vanes in said inlet casings connecting said bearings with 25 the walls of said casings.

30 8. In a double pump a central casing comprising an outer wall, a core, vanes interposed between said walls, and supporting said core, said walls and core forming between them a volute discharge passage and outwardly inclined annular passages which if extended would diagonally cross each other whereby they discharge diagonally into said 35 into said volute, and impellers in said outwardly inclined passages.

35 9. In a double pump a central casing comprising an outer wall, a core supported by vanes interposed between said walls and core, said walls and core forming between them a volute discharge passage and a pair of outwardly inclined annular passages so disposed relative to each other that if corresponding sides of each passage are extended 40 they will diagonally cross each other whereby fluid discharges diagonally into said 45 volute.

50 10. A double pump having a central casing formed of an outer wall, core and vanes interposed between said wall and core, said wall and core forming between them a volute discharge passage and outwardly inclined annular passages communicating therewith, impellers at the entrance to said annular 55 passages, a shaft extending through said core and carrying said impellers, tapering means upon said shaft and rotating therewith for preventing lateral displacement of said impellers and intake casing surrounding said 60 means and forming therewith vane free con-

tracting intake passages communicating with said impellers.

11. A double pump having a central casing formed of an outer wall, core and vanes interposed between said wall and core, said 70 wall and core forming between them a volute discharge passage and outwardly inclined annular passages communicating therewith, impellers at the entrance to said annular 75 passages, a shaft extending through said core and carrying said impellers, tapering means upon said shaft and rotating therewith for preventing lateral displacement of said impellers and intake casings surrounding said 80 means and forming therewith vane free contracting intake passages communicating with said impellers, said passages being preceded by volute contracting passages.

12. In combination with a casing having suction and discharge means, a double impeller connected at each side with said suction, and means in the suction at each side of said impeller and separated therefrom by conversion chambers for imparting rotational and axial velocity to the fluid before 90 entering the impeller.
